UNITED STATES PATENT OFFICE.

HERBERT SCHWANHÄUSSER, OF NUREMBERG, AND WALDEMAR SCHWANHÄUSSER,
OF MUNICH, GERMANY.

MACHINE FOR POLISHING PENCILS AND OTHER ROD-SHAPED BODIES.

Application filed June 8, 1926, Serial No. 114,523, and in Germany August 21, 1925.

For polishing pencils and other rod-shaped bodies one proceeds in such a manner that the pencils are either polished in a carriage which executes a reciprocating movement 5 underneath a polishing pad, or that the pencils are pushed the one after the other from a charging hopper by means of a ram through a reservoir containing liquid polish and then deposited for drying upon two 10 endless conveyor-bands on which they rest at both ends to be conveyed over a distance of several meters. At the end of this drying-path the pencils are removed by hand and placed into boxes to be carried back 15 to the charging-hopper into which they are fed again to be passed through the polishing process. According to another polishing method the pencils are placed upon a horizontal annular disk and deposited, after 20 a pre-determined part-rotation of said disk, into a box to be carried back by hand to the charging-hopper.

The invention has for its object, to make any work by hand unnecessary, and to carry 25 out automatically the removing of the pencils as well as the conveying back into the charging hopper. With this object in view a mechanism is arranged at the end of the drying path which is designed to receive a 30 certain number of pencils and to transfer the same upon a conveyor band which conveys the pencils back to the charging-hopper.

An improved machine for polishing pencils, comprising a charging-hopper, a reservoir 35 for liquid polish and a conveying band for drying is shown, by way of example, in the accompanying drawing in which:—

Fig. 1 shows in side elevation the machine with the improvement according to the 40 invention.

Fig. 2 is a plan view of Fig. 1.

Fig. 3 shows in rear elevation and on larger scale the conveying- and elevating- 45 mechanism.

Fig. 4 is a side elevation of Fig. 3.

The pencils to be polished are inserted into a charging-hopper 1 and fed by means of a ram 2 between two conveyor rollers 3

which push the pencils through a reservoir 4 containing the liquid polish. The pencils 50 are then deposited, head forward, upon the slowly moving endless conveying bands 5 arranged at a certain distance the one from the other and guided over pulleys 6, 7. These conveying bands are generally several 55 meters long. The polishing machine which has just been described is commonly used. The novelty consists in arranging, behind the pulleys 7 of the conveyor bands 5 a conveying- and elevating-mechanism which is 60 shown in Figs. 3 and 4 in detail and which is designed to convey the pencils to an endless band 8 situated above the drying bands and to convey the pencils back to the charging-hopper. 65

The elevating mechanism consists of two arms 9, 9. On the end of each arm a bucket 11 is suspended so that they can oscillate, said bucket being maintained in horizontal position by counter-weights 10. 70 These buckets 11 are of such width that they can just pass between the conveyor-bands 5. At the point over which the buckets pass stationary strippers 12 are arranged above the conveying bands 5, by 75 which strippers the pencils which, owing to the drying of the liquid polish, stick more or less strongly on the conveyor-bands, are loosened and adjusted parallel to one another owing to the progressing movement of 80 the drying bands.

In the circle along which the buckets move, a discharging-element consisting of two angular sheet-metal plates 14, 14 spaced the one from the other of the width of the 85 buckets 11, circulates above the horizontal position of the arms 9. The angular sheet metal plates 14, 14 are suspended by means of pivot pins 17 each on an arm 16 keyed on a shaft 17, said sheet metal plates 14, 14 90 being permanently held in vertical position by the action of counterweights 18. The elements 14 do not rotate individually but they are rotated in vertical position by the arms 16 around the axle 15. The elements 95 14 move at greater speed than the buckets

11 so that they remove the pencils from the bucket when passing over same. The shaft 15 is driven from a crossed belt-driving gear 19, 20, 21, the driving pulley 19 of which is keyed on a shaft 22 of the rear pulleys 7, 7 for the conveying bands 5, 5.

On the shaft 17 a spur wheel 23 (Fig. 6) is further keyed which gears with a toothed wheel 24 keyed on the axle 25 of the arm 10 crosses so that said arm crosses are rotated. Within the range of the discharging element 14, 14 descending from the extreme upper position downwards in the direction of rotation indicated, a sheet metal plate 26 15 arranged between said two discharging-shovels engages between the same and grips at the descending movement of the arms 16 the pencils on the discharging-shovel and brings the same downwards to deposit the 20 same upon the conveyor band guided over pulleys 27.

The operation of the mechanism is as follows:—

The pencils inserted into the charging-hopper 1 are pushed through the liquid polish in the reservoir 4 by the action of the ram 2 and by means of the rollers 3 and after having been coated with liquid polish the pencils are deposited upon the conveyor bands 5 at intervals of 3-5 cm. in accordance with the speed at which the conveyor bands move. The pencils striking against the strippers 12 are loosened from the conveyor bands, if they stick on the same, and directed so that they are parallel the one to the other. If about 14 to 16 pencils have collected at the strippers they are dropped into one of the buckets 11 coming from below and taken along. If the corresponding arm 40 9 is in a position inclined approximately 45° the pencils in the bucket 11 are caught by the discharging-elements 14 and lifted out of the buckets, as the discharging elements move ahead of said buckets. At the descending 45 of the discharging elements 14, 14 the pencils are deposited upon the sheet metal plate 26 which carries the same to the conveying band 8 to be conveyed again to the charging-hopper. As the outer surface of 50 the discharging-elements 14 moves at this occasion along the pencils lying upon the discharging sheet metal plate they are accordingly adjusted.

The polishing process is finished as soon 55 as the surface of the pencils has been sufficiently covered by repeated coating with liquid polish. The number of passages of the pencils through the liquid polish depends on their covering capability. After 60 a sufficiently thick coating has been produced the pencils are removed by hand from the top conveyor band.

As the amount of power, necessary for 65 removing and elevating of the pencils and for the conveying of the same back to the

charging-hopper is very little, the mechanism may be used in connection with any existing pencil-polishing machine without modification of the construction.

In polishing machines with circular drying-path the mechanism described may be used in such a manner that the strippers and the gripping and elevating mechanisms are arranged at the points at which the pencils were up to the present deposited into the box, a conveyor band or the like, leading from the gripping- and elevating mechanism to the charging hopper, being provided.

We claim:—

1. Machine for polishing pencils and other rod-shaped bodies, comprising in combination a reservoir for liquid polish, a charging-hopper in front of said reservoir, conveying bands for drying arranged behind said reservoir, a gripping- and elevating-mechanism arranged behind said conveyor bands, and a delivering conveyor band between said gripping- and elevating-mechanism and said charging-hopper so that, at the end of the drying path one or several pencils are gripped by said gripping- and elevating-mechanism and deposited upon said delivering conveying band to be brought back to said charging-hopper.

2. Machine for polishing pencils and other rod-shaped bodies, comprising in combination a reservoir for liquid polish, a charging-hopper in front of said reservoir, conveying bands for drying arranged behind said reservoir, strippers at the end of the drying path for loosening the pencils from said conveyor-bands for adjusting the same parallel to one another and for collecting a certain number of pencils, a gripping- and elevating-mechanism arranged behind said strippers, and a delivering conveyor band between said gripping- and elevating-mechanism and said charging-hopper so that, at the end of the drying path one or several pencils are gripped by said gripping- and elevating-mechanism and deposited upon said delivering conveying band to be brought back to said charging-hopper.

3. Machine for polishing pencils and other rod-shaped bodies, comprising in combination a reservoir for liquid polish, a charging-hopper in front of said reservoir, conveying bands for drying arranged behind said reservoir, strippers at the end of the drying path for loosening the pencils from said conveyor-bands for adjusting the same parallel to one another and for collecting a certain number of pencils, a gripping- and elevating-mechanism arranged behind said strippers, said mechanism consisting of two rotatable arm crosses, buckets oscillatably suspended at the ends of the arms, counterweights for maintaining said buckets in the horizontal position, discharging-elements mounted in the path of said buckets for lifting the pencils out of

said buckets, an inclined sheet metal plate between said discharging-elements, and a delivering conveyor band between said gripping- and elevating-mechanism and said charging-hopper so that, at the end of the drying path one or several pencils are gripped by said gripping- and elevating mechanism and deposited by said inclined plate upon said delivering conveying band to be brought back to said charging-hopper. 10
In testimony whereof we affix our signatures.
